UNITED STATES PATENT OFFICE.

FRANK C. HILKER, OF FORT WAYNE, INDIANA.

PNEUMATIC CUSHION.

1,382,831.

Specification of Letters Patent. Patented June 28, 1921.

Application filed April 11, 1921. Serial No. 460,567.

To all whom it may concern:

Be it known that I, FRANK C. HILKER, a citizen of the United States of America, and resident of Fort Wayne, in the county of Allen and State of Indiana, have invented certain new and useful Improvements in Pneumatic Cushions, of which the following is a specification.

This invention relates to improvements in 10 pneumatic pillows and cushions, and the object thereof is to construct a pneumatic sack in the form of a pillow or cushion so that when it is inflated it will tend to retain the flatness that is usual in the ordinary stuffed 15 pillow case or cushion. Inflated sacks commonly tend to become spherical or round when the pressure is sufficient to afford the required support, and the present construction is such as to permit inflation of the sack 20 with air pressure sufficiently high as to afford the required support without distorting the sack.

This object is accomplished by the construction illustrated in the accompanying 25 drawings in which:—

Figure 1 is a perspective view of the invention inflated;

Fig. 2 is a vertical cross section of the same;

Fig. 3 is a plan view of the invention in a modified form, a portion being shown broken away; and

Fig. 4 is a similar view of the invention showing another modification thereof.

The characters of reference hereinafter appearing pertain to the parts described and designated by corresponding characters on the drawings:

The invention is comprised of a closed 40 sack formed with top and bottom sheets 1 and 2 that are united at their edges with a seam 3. An air valve 4 is provided at one end of the sack through which the sack is inflated. The sheets are made of rubber, or 45 rubberized cloth, and each sheet is composed of laminæ of different degrees of stiffness. The inner lamina 5, shown in Fig. 2, is less pliant than the outer lamina 6. The inner lamina is partially cured by the usual process 50 of vulcanizing to a greater degree of

firmness than the outer lamina before the two are united and subjected to the final curing process, so that the inner lamina resists more than the outer lamina the tendency to bulge when the sack is inflated. As 55 shown in Fig. 2, the area of the inner lamina is restricted to the middle portion of the sheet, and therefore the corresponding areas of the sack tend to remain flatter than the marginal portions thereof. 60

In the modified form shown in Fig. 3 the sheets 7 and 8 forming the sack are each provided with a series of interior strips 9 formed in the same manner as the inner lamina in the first instance; and in the 65 modification shown in Fig. 4, the sheets 10 and 11, forming the sack, are each provided with a series of interior laminæ 12 of a similar character but differing in shape and arrangement. 70

In use, the sack is inflated with air through its valve to a pressure suited to the support required of it, and may be inserted in a pillow-case or cushion cover (not shown) as is the usual custom. Aside from its usefulness as a pillow and cushion, the invention may also serve in case of accident as a buoy when boating. 75

What I claim is:

1. A pneumatic sack for a pillow or cushion formed of two sheets of rubber the edges of which are united, and each sheet being composed of laminæ of different degrees of stiffness, the lamina of greater stiffness being of less area than that of the other lamina. 80

2. In a device of the class described, a sack having a valve and adapted to be inflated, the walls of the sack being formed of sheets each composed of laminæ of different degrees of stiffness, the lamina of greater stiffness being of less area than that of the other and adapted to resist the tendency of the sack to bulge when inflated. 90

In testimony whereof I affix my signature, in presence of two witnesses.

FRANK C. HILKER.

Witnesses:

MATILDA METTLER,
WALTER G. BURNS.
